(57) **CLAIM**

The ornamental design for a grill with modular component, as shown and described.

DESCRIPTION

FIG. 1 is a front, left perspective view of my new design for a grill with modular component shown in a grilling environment;

FIG. 2 is a top, right perspective view of the grill with modular component shown removed from the grilling environment;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

The broken lines in the drawings depict environmental subject matter only and form no part of the claimed design.
